UNITED STATES PATENT OFFICE.

JOSEPH B. SARGENT, OF NEW HAVEN, CONNECTICUT, ASSIGNOR TO SARGENT & CO., OF SAME PLACE.

DESIGN FOR A COFFIN-SCREW.

SPECIFICATION forming part of Design No. 13,437, dated November 14, 1882.

Application filed October 14, 1882. Term of patent 14 years.

To all whom it may concern:

Be it known that I, JOSEPH B. SARGENT, of New Haven, in the county of New Haven and State of Connecticut, have invented a new 5 Design for Coffin-Screws; and I do hereby declare the following, when taken in connection with accompanying drawings and the letters of reference marked thereon, to be a full, clear, and exact description of the same, and which 10 said drawings constitute part of this specification, and represent, in—

Figure 1, a top view of the head; Fig. 2, a top view of the plate; Fig. 3, a side view.

This invention relates to a design for the 15 ornamentation of the heads of screws for caskets and like purposes, and particularly to that class in which the ornament is of an emblematical character.

The design for the head consists in the representation of a bird with its head under its wing, and standing on the screw-plate, as 20 shown in the accompanying illustration, and more fully hereinafter described.

A represents the bird, having its head beneath its wing. In construction it is cast upon 25 the screw in the usual manner of casting coffin-screw heads, and so as to represent the bird as resting upon the head *a* of the screw. The plate is diamond-shaped, with a projecting 30 leaf ornament at the center of each of its four

sides, the sides inclined upward and toward the center, and representing a panel on each of the four inclined sides, and a panel at the center, on which the head of the screw rests, all as shown in the accompanying illustration. 35 The base, while designed with special reference to this particular head, other bases may be substituted for it, and also other heads may be used with this base. I therefore do not wish to be understood as limiting my invention to 40 the combination of this particular head and particular base.

What I claim is—

1. The design for screw-head, consisting in the representation of a bird with its head under its wing, as shown in the accompanying 45 illustration.

2. The design for base for coffin-screw, consisting of the diamond-shaped plate, the sides inclined upward toward the center and representing a panel, with a central diamond-shaped panel to form the top of the plate, and with a leaf ornament projecting from each of the four sides, as shown in the accompanying illustration. 50

JOSEPH B. SARGENT.
